UNITED STATES PATENT OFFICE.

ARTHUR LINZ, OF NEW YORK, N. Y., ASSIGNOR TO THE CHEMICAL FOUNDATION INCORPORATED.

METHOD OF DYEING.

1,414,031.

Specification of Letters Patent. Patented Apr. 25, 1922.

No Drawing.

Application filed September 29, 1921. Serial No. 504,155.

To all whom it may concern:

Be it known that I, ARTHUR LINZ, a citizen of the United States, and a resident of the borough of Manhattan, city, county, and State of New York, have invented an Improvement in Methods of Dyeing, of which the following is a specification.

My invention relates to an improved method of dyeing and has as an object the 10 obtainment of more permanent and fast to light dyeings upon leather, hides, and like materials, whereas such dyeings heretofore have been of a relatively fugitive and unstable character.

When leather, hides, and like materials, have been dyed in accordance with the ordinary methods heretofore used, the colors are not always permanent and are sometimes affected by light. It is an object of my improved method to obviate these possible objections and it is shown that when leather, hides, and like materials are treated in accordance with my method, the colors are relatively faster and more permanent.

The dyeings hereinbefore referred to depend upon the formation of color lakes, and I have discovered a procedure for dyeing of leather, hides, and like materials through the formation of color lakes produced by the 30 employment of complex acids containing a difficultly fusible metal such as tungsten and molybdenum together with phosphorus and silicon. Such acids, for instance, may be phosphotungstic acid and silicotungstic acid, and of these acids there may be employed those known as the dideci and the luteo acids. However, instead of the complex acids themselves, there may be employed salts of the same, such a sodium 35 salts, for example, sodium prototungstate and sodium phosphomolybdate.

The process according to my invention comprises an after treatment of the dyeings on leather, hides, and like materials with 45 complex acids containing a difficultly fusible metal such as the phospho and silicic acids hereinbefore referred to, and when such dyeings are accomplished it is ascertained that they are relatively permanent.

50 The following examples will serve as illustrative embodiments of a manner in which my process may be carried into practical effect:

Example I.

55 Take a quantity of leather, hides, and like

materials, (e. g. 100 lbs.) mordanted with tannic acid and an antimony salt and dye in the usual manner with say about one-half pound of methyl violet. The product has a 60 beautiful purple hue which, however, is fugitive and of a transitory nature. It is then treated by placing in a solution containing five pounds of sodium phospho tungstate or of five pounds of sodium phospho molybdate 65 and three hundred gallons of water. The subsequent treatment may be done in the usual manner at ordinary temperature although it may be considered preferable to carry out the treatment at a raised temperature about 70° C. 70

Example II.

A similar result as outlined in Example 75 I may be obtained by mordanting leather, hides, and like materials in the usual manner with a solution containing sodium phospho tungstate or sodium phospho molybdate or the complex acids themselves may be used 80 instead of the salts in dilute form. This may be carried out for example by treating in a drum, leather, hides, and like materials with a solution of the above-mentioned products. Then, dyeing the leather, hides, and like 85 materials so mordanted in the usual manner with coloring matters, in this way producing the same effect as previously described or in other words, producing on or in treated materials, the color lake formed by means of 90 phospho tungstic acid, phospho molybdate acid or by means of salts of these complex acids.

When it is desired to employ the salts of the complex acids it may be found preferable to add to the tanning bath a suitable organic or inorganic acid, which acid shall be capable of freeing phosphoric, tungstic, molybdate and silicic acids from their respective salts for which purpose there may 100 preferably be used hydrochloric, sulfuric and acetic acids which will not effect the coloring matter to be used, and it will be understood, of course, that such acid may be entirely dispensed with if the formation of the 105 color lake takes place satisfactorily without its use, and this may be determined by simple experiment.

The dyestuffs which may be preferably utilized in my process are usually designated 110 as the basic coal tar dyes and in addition to methyl violet set forth in the above exam-

ple, there may be employed such dyestuffs as auramine, phosphin, chrysoidin, Bismarck brown, malachite green, emerald green, methylene blue, Victoria blue, crystal violet, saffranine and basic fuchsin, but it will be understood that my process is not limited to the specific class or the specific dyes herein mentioned, but may be employed for such dyes as will give a permanent and fast color through fixation by means of the compounds set forth.

I claim:

1. The process of dyeing leather, hides, and like materials, which comprises dyeing the said material with a basic dyestuff and then treating said dyed materials with a solution of a complex acid containing a difficultly fusible metal.

2. The process of dyeing leather, hides, and like materials, which comprises dyeing the said materials with a basic dyestuff and then treating said dyed materials with a complex acid containing tungsten.

3. The process of dyeing leather, hides, and like materials, which comprises dyeing the said materials with a basic dyestuff and then treating said dyed materials with a complex acid containing phosphorus and a difficultly fusible metal.

4. The process of dyeing leather, hides, and like materials, which comprises dyeing the said materials with a basic dyestuff and then treating said dyed materials with a complex acid containing phosphorus and tungsten.

5. The process of dyeing leather, hides, and like materials, which comprises dyeing the said materials with a basic dyestuff and then treating said dyed materials with a complex compound containing a difficultly fusible metal.

6. The process of dyeing leather, hides, and like materials, which comprises dyeing the said materials with a basic dyestuff and then treating said dyed materials with a complex compound containing phosphorus and a difficultly fusible metal together with an acid capable of freeing the acid from such compound.

7. The method of dyeing leather, hides and like materials, which comprises dyeing the said materials with a basic dyestuff and then treating with a solution of a complex acid containing phosphorus and a difficultly fusible metal.

8. The method of dyeing leather, hides and like materials, which comprises dyeing the said materials with a basic dyestuff and then treating with a solution of a complex acid containing phosphorus and tungsten.

9. The method of dyeing leather, hides and like materials, which comprises dyeing the said materials with a basic dyestuff and then treating with a solution of a complex compound containing a difficultly fusible metal, together with an acid capable of freeing the acid from such compound.

10. The method of dyeing leather, hides and like materials, which comprises dyeing the said materials with a basic dyestuff and then treating with a solution of a salt of a complex acid containing a difficultly fusible metal, together with an acid capable of freeing the acid from such compound.

11. The method of dyeing leather, hides and like materials, which comprises dyeing the said materials with a basic dyestuff and then treating with a solution of a salt of a complex acid containing phosphorus and tungsten.

12. The method of dyeing leather, hides and like materials, which comprises dyeing the said materials with a basic dyestuff and then treating with a solution of a salt of a complex acid containing a difficultly fusible metal.

13. The method of dyeing leather, hides and like materials, which comprises dyeing the said materials with a basic dyestuff and then treating with a solution of a salt of a complex acid containing phosphorus and tungsten, together with an acid capable of freeing the acid from such compound.

In testimony whereof, I have signed my name to this specification this 27th day of September, 1921.

ARTHUR LINZ.
